UNITED STATES PATENT OFFICE.

PAUL SOBLIK, OF MAGDEBURG, GERMANY, ASSIGNOR TO FRANZ KOCH AND MARTHA SOBLIK,
OF MAGDEBURG, GERMANY,

SOSTENUTO PIANO.

No. 913,990.

Specification of Letters Patent.

Patented March 2, 1909.

Application filed October 7, 1907. Serial No. 396,316.

To all whom it may concern:

Be it known that I, PAUL SOBLIK, instrument-maker, a subject of the German Emperor, King of Prussia, residing at 44^a Kaiserstrasse, Magdeburg, Germany, have invented certain new and useful Improvements in Sostenuto Pianos, of which the following is a specification.

My invention relates to a mechanical action 10 for key controlled sostenuto pianos, the object being to produce a continuing sounding of the string or chord during the pressing of the key.

It is desirable for certain pieces of music 15 and under special circumstances for instance in large rooms, for choirs and the like, to hold the sound of the stringed instrument for a certain time at the same loudness in order to obtain an effect similar to that obtained with 20 pipe-instruments such as organs and harmoniums. This object is obtained according to the present invention by an uninterrupted oscillation of the hammer during the pressing of the corresponding key whereby a 25 continuous striking of the string is obtained.

The annexed drawing shows one embodiment of my invention, and in this drawing: Figure 1 is a side elevation, Fig. 2 a front elevation of the hammer device, Fig. 3 a plan 30 view of a mechanical piano action constructed according to the principles of the present invention.

As shown by this drawing the hammers *a* are hingedly connected at their front *b* to the 35 upper end of a movable hammer carrier which forms a lever *c* hingedly connected to a rail *d* at its lower end and held in its position of rest by a spring *d* and pushed back against the action of the said spring by the 40 key *h* through sticker *g* and bell crank *f*, *e*, as soon as the key has been pressed down.

Connected with the hammer carrying lever *c* is a roller *i* which by means of a crank pin *k* actuates a connecting rod *l* connected with 45 the hammer butt *b*. In front of the series of rollers *i* and rotatably supported is a cylinder *m* which receives a rapid rotary motion by actuating devices arranged in the lower part 50 of the instrument. These actuating devices may for instance comprise levers, cranks and fly wheels arranged and acting as the driving devices of sewing machines. When the key *h* is depressed, the roller *i* is pressed against the cylinder *m* and owing to the action of the 55 crank *k* the hammer receives a rapid and posi-

tive oscillating motion or vibration so that the string is acted upon by a continuous succession of blows given all with the same force.

The diameters of the rollers and the cylinder are preferably chosen in such a manner 60 that the number of hammer blows be in a determined relation to the number of vibrations of the strings so that the lower tones receive per time unit a lower number of sounding blows than the high tones. This object may 65 be realized by a conical form of the driving cylinder and a corresponding enlarging toward one side of the diameters of the rollers while the eccentricity of the crank pin remains the same. 70

Having now fully described my said invention what I claim and desire to secure by Letters Patent is:

1. In a mechanical action for key-controlled sostenuto instruments the combination with the hammer, the rail and the key of a hammer-carrier hingedly connected to the rail, the hammer butt hingedly connected to the said hammer carrier, a spring for the hammer carrier, a crank mechanism 75 carried by the hammer carrier and connected to the hammer butt to cause the latter to oscillate, an actuating member for the said crank mechanism and means arranged between the hammer carrier and the said key 80 to move the hammer carrier against the action of the hammer carrier spring when the key is depressed so as to cause the said actuating member to actuate the crank mechanism, substantially as and for the purpose 85 set forth. 90

2. In a mechanical action for key controlled sostenuto instruments the combination with the hammer, the rail and the key of a hammer carrier hingedly connected to 95 the rail, a spring for the carrier the hammer butt hingedly connected with the hammer carrier, a roller revolvably carried by the carrier, a crank pin on the said roller, a connecting rod interposed between the crank 100 pin and the hammer butt, an actuating cylinder revolvably mounted in front of the roller, means for rapidly rotating the cylinder and means interposed between the hammer carrier and the said key adapted to 105 move the hammer against the action of the carrier spring when the key lever is depressed so as to cause the roller to contact with the said actuating cylinder, substantially as and for the purpose set forth. 110

3. In a mechanical action for key controlled sostenuto instruments the combination with each hammer, the rail and each key of a hammer carrier hingedly connected 5 with the rail, a spring for the carrier, the hammer butt hingedly connected with the hammer carrier, a roller revolubly mounted on the hammer carrier, a crank pin on the roller, a connecting rod connecting the 10 crank pin with the hammer butt, an actuating cylinder revolubly mounted in the front of the roller of each hammer carrier, means actuated by foot of the player of the instrument for rapidly rotating the said cylinder, 15 and a system of levers interposed between the hammer carrier and the said key to move the hammer carrier against the action of the carrier spring when the said key is depressed, so as to cause the roller to contact with the 20 said actuating cylinder, substantially as and for the purpose set forth.

4. In a mechanical action for key controlled sostenuto instruments the combination with each hammer, the rail and each 25 key of a hammer-carrier hingedly connected

with the rail, a spring for the said carrier, the hammer butt hingedly connected with the hammer carrier, a roller revolubly mounted on the hammer carrier, a crank pin on the roller, a connecting rod connecting the 30 the said crank pin with the hammer butt, a conical actuating roll revolubly mounted to engage the said roller, having its larger diameter on the side of the higher tones, means actuated by foot by the player of the instrument for rapidly rotating the said conical roll, and a system of levers interposed between the hammer carrier and the said key to move the hammer carrier against the carrier spring, so as to cause the roller to contact with the said actuating roll as long as the key is depressed, substantially as and for the purpose set forth. 35

In testimony whereof I have signed my name to this specification in the presence of 40 two subscribing witnesses.

PAUL SOBLIK.
